Primary Examiner — Steven J Czyz(74) *Attorney, Agent, or Firm* — Getz Balich LLC(57) **CLAIM**

The ornamental design for a tablet dispenser for medications, as shown and described.

DESCRIPTION

FIG. 1 is a front perspective view of a tablet dispenser for medications;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top side elevation view thereof;

FIG. 7 is a bottom side elevation view thereof;

FIG. 8 is an exploded front perspective view thereof;

FIG. 9 is an exploded front elevation view thereof;

FIG. 10 is an exploded rear elevation view thereof;

FIG. 11 is an exploded left side elevation view thereof; and,

FIG. 12 is an exploded right side elevation view thereof.

The broken lines depict portions of the article that form no part of the claimed design.
